UNITED STATES PATENT OFFICE.

ADOLF KREGLING, OF STRATFORD, CONNECTICUT.

DESIGN FOR A MUSICAL INSTRUMENT.

55,058.

Specification for Design.

Patented May 4, 1920.

Application filed January 20, 1920. Serial No. 352,865. Term of patent 7 years.

To all whom it may concern:

Be it known that I, ADOLF KREGLING, a citizen of the United States, residing at Stratford, in the county of Fairfield and State of Connecticut, have invented a new, original, and ornamental Design for a Musical Instrument, of which the following is a specification, reference being had to the accompanying drawing, forming a part thereof.

Referring to the drawing—

I claim—

The ornamental design for a musical instrument as shown.

ADOLF KREGLING.
